APPLIQUÉ TYPE PANEL FOR CABINET DOORS OR THE LIKE

John R. Morgan, Wheeling, Ill., assignor to Amerock Corporation, Rockford, Ill., a corporation of Connecticut

Filed Nov. 23, 1966, Ser. No. 4,785

Term of patent 14 years

(Cl. D13—1)

FIG. 2 is a top plan view of the medallion.

FIG. 3 is a sectional view taken along the line 3—3 in FIG. 1.

FIG. 4 is a side view as seen from the left in FIG. 1.

FIG. 5 is a sectional view taken along the line 5—5 in FIG. 1.

FIG. 6 is a sectional view taken along the line 6—6 in FIG. 1.

I claim:

The ornamental design for an applique type panel for cabinet doors or the like, as shown.
